G. K. Höhn,
his ATTORNEY.

UNITED STATES PATENT OFFICE.

FREDERICK WACHTER, OF JERSEY CITY, NEW JERSEY.

CHLOROFORM-DROPPER.

No. 823,283.

Specification of Letters Patent.

Patented June 12, 1906.

Application filed October 12, 1905. Serial No. 282,886.

To all whom it may concern:

Be it known that I, FREDERICK WACHTER, a citizen of the United States of America, and a resident of Jersey City, in the county of 5 Hudson and State of New Jersey, have invented certain new and useful Improvements in Chloroform-Droppers, of which the following is a specification.

This invention has reference to improvements in liquid-fluid droppers, and pertains particularly to a novel chloroform-dropper.

Chloroform and other light and easily volatile liquids which are used as anesthetics and anodynies are generally dispensed in small 15 quantities, preferably drop by drop. This is done in order to volatilize and diffuse the anesthetic freely and rapidly in the atmosphere and to apply to the patient a minute quantity only at a time. For the purpose of accomplishing this the anesthetics are dispensed by means of dropping devices from 20 which the liquid flows in drops. These liquids are specifically light, thin, and very mobile, and therefore escape easily through the 25 finest openings and between the walls of valves of general construction, if same form part of a dropping device. The liquid fluid—chloroform, for instance—then not only falls in drops from the orifice of the device, but 30 issues from the outside parts of the valve and is spent uselessly and wasted.

It is the object of this invention to avoid the described deficiencies and provide a novel chloroform-dropper which issues the 35 liquid fluid solely through the outflow-orifice of the dropper.

Owing to the construction of my novel dropper no leakage can occur and no chloroform is wasted.

40 The device is simple in construction and can be manufactured cheaply.

The invention further consists in the construction of details and arrangements of parts.

45 It is illustrated in the accompanying drawings, in which—

Figure 1 represents in elevation a liquid-fluid dropper which embodies my invention. Fig. 2 illustrates, on an enlarged scale, in vertical section the upper part of my device. Fig. 3 is a cross-section on line $x-x$ of Fig. 2; and Fig. 4 is a cross-section on line $y-y$ of Fig. 2, the stopper having been turned ninety degrees.

50 Similar characters of reference denote like parts in all the figures.

My novel liquid-fluid dropper consists, essentially, of a fluid-receptacle or bottle, a metal tube secured to the neck of said bottle and having a narrower upper portion, which 60 is threaded on the inside, and a compound metal stopper adapted to be attached to the bottle and embodying my improvements. This stopper comprises elements for the ingress of air into the bottle, the outflow of the 65 liquid fluid, and a valve device which is adapted to open and tightly close the dropper.

In the drawings, a represents the liquid-fluid reservoir or bottle, which is of the usual 70 form for such devices. It is flat on one side and somewhat bulged on the other. This form of bottle is convenient when it is desired to carry same in the pocket. The neck b of the bottle is provided on its upper portion with a metal tube c , which is cemented thereto or otherwise secured. This metal tube has a narrow top portion c' , which is 75 threaded on the inside.

The compound stopper consists of two 80 parts, an inner part or plug d , and an outer part or shell, which has a solid bottom portion. The lower portion d' of the plug d is a solid metal rod circular in shape and of even diameter throughout. It has an enlarged 85 rim d'' at the top, which is roughened, ribbed, or knurled, so that it may be tightly gripped. A small boring e passes through the plug, and a small tube f is attached to the top part of the plug, so that its opening coincides with the 90 boring e . The upper portion of the tube f is bent outwardly and has an outflow, orifice, or aperture at the end. The channel or boring e and the tube f form part of the passage-way of the liquid fluid during the operation of 95 the device. A second boring g , somewhat larger than the boring e , is provided in the plug, which connects with a second small tube h , also somewhat larger than the tube f , and bent outwardly at the top in the opposite direction to said tube f . The boring g and the tube h coincide and form part of the passage-way of the air, which rushes into the bottle 100 when the device is used. In the center bottom portion of the plug there is a threaded opening adapted to receive a screw. A small pin i is secured in the top portion of the plug near the rim d'' and at a right angle to the tubes f and h .

The outer part or shell of the compound stopper has a tubular top portion j , which fits exactly over the lower portion d' of the 110

plug *d*, and an enlarged bottom portion *n*, which is solid. The lower portion *n* forms a shoulder *m* at the top, it is reduced in width at the bottom and provided there with a screw-thread which fits the threaded top portion *c'* of the tube *c* on the neck of the bottle. Two incisions *k l* are made on the top portion of the shell, in one of which rests the pin *i*, as shown in Fig. 1. A leather washer *o* is provided on the threaded portion of the part *n* which tightens the bottle there. The solid part *n* has three borings—one in the center which serves for passing through a screw and coincides with the central opening in the plug *d*. The small boring *e'* coincides with the boring *e* in the plug *d*, while the larger boring *g'* coincides with the larger boring *g* of said plug. A long tube *p* is secured to the part *n* corresponding to the boring *g'* and extending down to nearly the bottom of the bottle. This tube completes the passage-way for the inrushing air. The passage-way for the liquid fluid is completed by the boring *e'*. Within the tube *j* and on the top of the part *n* there is a leather washer *q*, which also has three openings *e² g²*, and a central one, which correspond to and coincide with the borings above described. This washer tightens the device completely. A screw *r* passes through the plug *n* into the central opening of the plug *d*. On the lower portion of the screw *r* there is a circular spring *s*, which is held in position by the shoulder *r'* of the screw *r*, its upper end resting against the bottom surface of the part *n*. The spring *s* tends to draw the plug *d* tightly down upon the washer *q*, whereby any leakage of the liquid fluid is prevented.

Assuming now that the device is screwed together and in the position shown in Figs. 1, 2, and 3, then same is open and ready for use. When the bottle is held with its openings downward, then air rushes in through the tube *h*, the channels *g g'*, and the long tube *p*. At the same time the liquid fluid passes through the channels *e' e* and the tube *f*, and drops out through the orifice of the latter. No fluid—say chloroform—can escape, because the two parts forming the stopper are held firmly together by the screw *r* and spring *s* and the leather washer *q* tightens them completely. When it is desired to close the device, then the plug *d* is held firmly on the rim *d²* and turned around for about ninety degrees. The pin *i* of the plug *d*, which originally was in the incision *k*, is thereby transferred into the incision *l*, where it stops. The channels *e g* have accordingly been removed and turned for about ninety degrees and no longer coincide with the channels *e' g'*, whereby the

device is closed. The plug *d* thus acts as the key of a valve, and the distance of the openings in the channels from each other is relatively large, thus assuring the tight closing of the device. The relative location of the upper and lower channels in the closed device is shown in Fig. 4.

Having thus described my invention, I claim as new and desire to secure by Letters Patent—

1. A liquid-fluid dropper comprising a fluid-receptacle, a compound stopper and valve consisting of an inner part or plug with pin, and an outer shell having two incisions in its top which said pin engages alternately and a solid bottom part, the two parts having coinciding channels, and two small tubes connecting one each with one coinciding set of channels, all so arranged that the location of the channels in the plug may be changed by turning it ninety degrees, whereby the device is opened and closed.

2. A chloroform-dropper comprising a chloroform receptacle or bottle having a metal tube secured to its neck, a compound stopper and valve made in two parts having coinciding channels for the ingress of the air and the outflow of the chloroform, a leather washer with openings coinciding with said channels located between the two parts of the stopper, and a central pin with spring adapted to force said two parts together, all so arranged that the location of the channels in the upper part may be changed by turning said part ninety degrees whereby the device is opened and closed.

3. A chloroform-dropper comprising a chloroform-bottle having a metal tube secured to its neck, a compound stopper and valve adapted to be joined tightly to the bottle and made in two parts, an inner part or plug with pin and an outer shell having a solid bottom part and two incisions in its top in which the pin of the plug locates alternately, both parts having coinciding channels for the ingress of the air and the outflow of the chloroform, a leather washer between the two parts of the stopper with openings coinciding with said channels, and a central pin with spring adapted to force said two parts together, all so arranged that the location of the channels may be changed by turning said plug ninety degrees in a horizontal plane whereby the device is opened and closed.

Signed at New York, N. Y., this 5th day of October, 1905.

FREDERICK WACHTER
